US0D1110508S

(12) **United States Design Patent** (10) **Patent No.:** **US D1,110,508 S**
(45) **Date of Patent:** **** Jan. 27, 2026**

(54) **ORTHODONTIC MINIPLATE**

(71) Applicant: **KING SAUD UNIVERSITY**, Riyadh (SA)

(72) Inventors: **Ali Saleh Aljhani**, Riyadh (SA); **Lama Ahmed Alkahlan**, Riyadh (SA)

(73) Assignee: **KING SAUD UNIVERSITY**, Riyadh (SA)

(**) Term: **15 Years**

(21) Appl. No.: **29/966,928**

(22) Filed: **Oct. 7, 2024**

(51) **LOC (15) Cl.** 24-02

(52) **U.S. Cl.**

USPC **D24/180**

(58) **Field of Classification Search**

USPC D24/152, 176, 180, 186, 220, 221, 232

CPC A61C 7/00; A61C 8/0031; A61C 8/0096

See application file for complete search history.

(57) **CLAIM**

The ornamental design for an orthodontic miniplate as shown and described.

DESCRIPTION

FIG. 1 is a perspective view of an orthodontic miniplate showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
